RAZOR HOLDER

Martin B. Schinker, 811 Glacier Heights Road,
Youngstown, Ohio

Filed May 26, 1965, Ser. No. 85,459

Term of patent 3½ years

(Cl. D17—3)

The figure is a front perspective view of a razor holder showing my new design.

The opposite side of that shown is substantially identical thereto except for the reverse curve to the holder member as shown on the drawing.

I claim:

The ornamental design for a razor holder, as shown and described.
